UNITED STATES PATENT OFFICE.

GEORG NIKEL, OF GEISLINGEN, GERMANY, ASSIGNOR TO ALBERT F. DIETZ, OF NEW SALEM, NORTH DAKOTA.

ELEVATOR-BUCKET.

SPECIFICATION forming part of Letters Patent No. 788,590, dated May 2, 1905.

Application filed December 2, 1904. Serial No. 235,156.

To all whom it may concern:

Be it known that I, GEORG NIKEL, a subject of the Emperor of Germany, residing at Geislingen, in the Kingdom of Würtemberg, Empire of Germany, have invented a new and useful Elevator-Bucket, of which the following is a specification.

My invention relates to that class of buckets or cups which are commonly attached in series upon an endless chain or belt for the purpose of conveying grain or other loose material in bulk from one point to another.

My invention has for its object the elevation of a maximum amount of grain in the cheapest and most convenient way and with the least expenditure of power. As compared with the elevator-buckets now in common use the invention under consideration is believed by me to be cheaper and simpler in construction, and the buckets are capable of being placed closer together upon the carrier-belt, while they may be operated with less power and more rapidly and with greater efficiency in filling and emptying the load.

In the accompanying drawings, forming part of this specification, Figure 1 is a perspective view of a complete bucket embodying my invention. Fig. 2 is a side elevation of the bucket, and Fig. 3 is a plan of the blank which when bent into shape constitutes the entire bucket.

The lower part A of this bucket has the form of an inverted pyramid, which form facilitates both the filling and the emptying of the buckets, as well as the placing of the buckets close together upon the elevator chain or belt, and makes possible the use of the cups for all kinds of material with like success. The upper part or mouth B of the bucket, as shown, consists of four sides, three of which are substantially vertical, while the fourth (which is attached to the belt) forms a continuation of one of the inclined faces of the pyramid, and I have found that this construction makes an undue spreading of the contents after emptying impossible and at the same time increases the capacity of the bucket.

It is obvious to those skilled in the art that

the construction of the completed device (shown in Figs. 1 and 2) from the blank (shown in Fig. 3) is simple and cheap, without in any way impairing the strength or efficiency of the bucket. The blank is bent along the broken lines C, so that the faces D D' are brought together. The flanges E are turned up (from the lines C') into vertical position to form, with the upper part of the united faces D D' of the blank, the walls of the mouth of the structure, which is substantially quadrangular in section, while the triangular portions of the blank form the converging sides of the bottom of the bucket.

The above-described walls of the bucket's mouth are riveted or bolted together at F F', and the completed buckets may then be attached by bolts or otherwise to the carrier through the openings G G', which respectively register with one another.

In use the buckets are attached to the endless chain or belt in the usual manner, except that they may be placed nearer together than is possible with the devices now in use.

It is obvious that the device above described may be used for conveying many other substances than grain, and I do not confine the claims to use on grain-elevators.

Having now described my invention, what I claim as new, and desire to protect by Letters Patent, is—

1. An elevator-bucket, the lower portion of which, when inverted, has the form of a pyramid, while the upper portion has substantially vertical sides, whereby both the filling and emptying of the material is accomplished with a minimum amount of energy.

2. An elevator-bucket, constructed of a single blank and consisting of a lower portion in the form of an inverted pyramid and an upper portion, one wall of which is an extension of the rear wall of the pyramid, while the other walls of said upper portion are vertical.

3. A pyramid-bucket for grain-elevators, the upper portion of which has substantially vertical walls, whereby the spreading of the contents, after leaving the bucket, is prevented.

4. An elevator-bucket, comprising a lower

and an upper portion, the walls of said lower portion converging toward a point at its base, while the upper portion forms a mouth, one wall of which is an extension of one side of the converging base, while the other sides are substantially vertical.

5 In testimony whereof I have signed my name

to this specification in the presence of two subscribing witnesses.

GEORG NIKEL.
